UNITED STATES PATENT OFFICE.

GROVER C. KIDWELL, OF MADISON, INDIANA.

SHIPPING JACKET FOR ICE-CREAM CONTAINERS.

Application filed August 15, 1925. Serial No. 50,497.

This invention relates to shipping jackets for ice cream containers and the like and has for an important object thereof the provision of a jacket, eliminating the necessity of employing ice in the shipping of such containers.

An important object of the invention is to produce a device of this character which will be light in weight and provide a thorough insulation for the can.

A still further object of the invention is the provision of a device of this character which may be very readily produced and cheaply constructed.

These and other objects I attain by the construction shown in the accompanying drawing, wherein for the purpose of illustration is shown a preferred embodiment of my invention and wherein:

Figure 1 is a perspective view of an ice cream can container constructed in accordance with my invention;

Figure 2 is a vertical sectional view therethrough;

Figure 3 is a partial transverse sectional view showing the construction of the pockets.

Referring now more particularly to the drawings, the numeral 10 generally designates a base for the container which consists of two wooden disks 11 and 12 having arranged therebetween a layer of sheet cork 13. The side walls of the container comprise inner and outer canvas tubes 14, 15, the space between which is divided into a plurality of pockets 16 for the reception of a ground cork filling 17. At its upper end, the wall decreases in thickness providing a flaring mouth 18.

At their lower ends, the inner and outer walls are firmly secured to the base 10. A strap 19 surrounding the lower end of the outer wall is extended down about the sides of the base and this strap being secured to the base through the outer wall. Secured to the strap 19, at their lower ends, are handle straps 20 consisting of a length of leather or the like bent intermediate its ends and secured from a point adjacent the bend throughout its length to the canvas covering, as indicated at 21. The unattached portions 22 form handles for shifting the jacket. Adjacent their upper ends, these straps are preferably likewise secured to a further strap 23 encircling the jacket in spaced relation to the upper end thereof,

this strap having projecting upwardly therefrom at spaced intervals buckle straps 24, the purpose of which will presently appear.

A cover is provided comprising a canvas section forming a top 25 having depending from its edges a flap 26 forming a flange to receive the upper end of the jacket. This cover, upon its under surface, is lined with cork 27 and canvas 28 after the manner of constructing the side walls and its under surface is shaped to conform to the flaring of the upper end walls of the jacket and to the shaping of the cap of an ice cream can, as shown. The lower end of the flange is encircled by a strap 29, all of which, except the end portions, is secured to the flange at 30. The end portions have a buckle engagement with one another, as at 31, so that the flange may be drawn tightly against the sides of the jacket. Depending from this strap 29 are short straps 32 for coaction with the short straps carried by the jacket encircling strap 23 to draw the cap or cover firmly into position upon the jacket.

The pockets 16 are preferably formed by securing to the inner wall 14 vertically extending strips of fabric, indicated at 33. The outer ends of these strips are in turn secured to a layer of fabric lying within the outer wall 15 and in the form of a tube. By this construction, each of the pockets is provided with radially extending walls and each pocket is entirely separate and distinct from the remaining pocket so that rupture of one of the pockets will not affect any of the other pockets.

It will be obvious that the particular structure hereinbefore set forth is obviously capable of a certain range of change and modification and I accordingly do not limit myself to such specific structure except as hereinafter claimed.

I claim:

1. In a heat insulating shipping jacket, a container wall including spaced continuous inner and outer walls of flaccid material, strips of flaccid material connecting the inner and outer walls of the container producing between said walls a plurality of vertically extending pockets, a heat insulating material tightly filling said pockets, and rendering the container wall self-sustaining and substantially rigid, a bottom for the receptacle and a cover therefor.

2. In a heat insulating shipping jacket,

continuous annular concentric walls of flaccid material secured at their lower ends to a rigid heat insulating bottom, vertically extending strips of flaccid material extending between said walls from top to bottom thereof at circumferentially spaced intervals and dividing the space between said walls into a plurality of pockets, the side edges

of said strips being secured to said walls, a cork filling for each of said pockets tightly filling the pockets and rendering said side walls rigid, and a cover for the container.

In testimony whereof I hereunto affix my signature.

GROVER C. KIDWELL.
